UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,280,751.

Specification of Letters Patent. Patented Oct. 8, 1918.

Application filed September 25, 1917. Serial No. 193,104.

To all whom it may concern:

Be it known that I, KENNETH S. JOHNSON, a citizen of the United States, residing at Jersey City, in the county of Hudson and 5 State of New Jersey, have invented certain new and useful Improvements in Telephone Systems, of which the following is a full, clear, concise, and exact description.

This invention relates to telephone systems, and more particularly to operators' telephone circuits for use in telephone systems.

When establishing connections between toll and local telephone lines, it is necessary 15 for an operator in supervising such connections to connect the telephone set across the circuit established between two subscribers. Under such circumstances it is essential that the transmission efficiency of the circuit between the two subscribers be not materially decreased by such connection of the operator's telephone set.

An object of this invention is, therefore, the production of an operator's telephone 25 circuit which when connected to a telephone line, is highly efficient for both talking and receiving, and which when bridged across the talking circuit between subscribers for monitoring purposes will not materially decrease the transmission efficiency of the talking circuit.

In accordance with this invention an operator's telephone circuit is provided with an induction coil having a secondary winding with a receiver normally connected 35 across a high impedance section thereof. Upon the actuation of a key or switch associated with an operator's link circuit connecting two telephone lines together, the receiver is connected in bridge of a low impedance section of the secondary winding and thereby increases the impedance of the bridge including the secondary winding, which as a result of the actuation of the 40 switch is connected across the talking circuit extending between the two subscribers.

This invention is illustrated in the accompanying drawing in which there is shown a common battery local telephone line A and 45 a local battery toll telephone line B, which are suitably connected together by means of a cord circuit C. It will be understood, of course, that a number of lines similar to lines A and B terminate at the same central office, at which are provided a number of

cord circuits similar to C, but for convenience only the two lines and the one cord circuit have been shown.

An operator's telephone set D, common to a plurality of cord circuits C, comprises an 60 induction coil 20 having a primary 21, in circuit with which is a battery 22; an impedance coil 23 and a condenser 24. A transmitter 25 is connected as shown, so as to receive battery supply from battery 22 65 through an impedance coil 23, and to be in the talking circuit which includes the primary 21 of the induction coil and the condenser 24. Upon the same core with the primary winding 21 is wound a secondary 70 winding comprising four sections 26, 27, 28 and 29, all of which are connected in series aiding. The impedance of section 27 is of the same value as that of section 28, while the impedance of sections 26 and 27 in series 75 is of the same value as that of sections 28 and 29 in series. The resistance of sections 26 and 29 is low compared to that of sections 27 and 28. A receiver 30 has one terminal connected to the junction point between sections 26 and 27, and the other terminal thereof normally connected through the normal right-hand contact of relay 40 to the junction point between sections 28 and 29. With the receiver connected in this 80 manner, the secondary winding of the induction coil 20 acts as an auto-transformer for receiving incoming currents. The middle point of the secondary winding at the junction point between sections 27 and 28 85 is grounded to balance both sides of the operator's telephone circuit, thereby to eliminate inductive noises in the receiver from ringing current traversing adjacent leads in the switchboard. The outer terminals of 90 sections 29 and 26 of the secondary winding are connected to conductors 31 and 33 respectively terminating in normally open contacts of a listening key 9 and normally open contacts of a slow-to-operate relay 41 95 which is common to a plurality of cord circuits. A condenser 32 is included in the conductor 31 and a similar condenser 34 is included in the conductor 33, while coils 35 and 36 of high resistance are legged from the conductors 31 and 33 to ground and in bridge of the condensers 34 and 32 and cooperate with the condensers to prevent interference with other apparatus in the individual cord circuits and to balance the op- 100 110

erator's telephone circuit as clearly set forth in U. S. Patent No. 1,232,884, issued to Oscar E. Benson, July 10, 1917. The junction point between sections 27 and 28 of the secondary winding and the junction point between resistance coils 35 and 36 are normally grounded through the left-hand normal contact of relay 40.

If the operator desires to converse with either subscriber, listening key 9 is actuated to connect the tip and ring conductors 33 and 31 of the telephone set with the talking strands of the cord circuit, thereby bridging the telephone set across the circuit. Should the operator merely desire to bridge the receiver of the telephone set across the circuit established between A and B for the purpose of properly supervising the connection between the subscribers or for any other purpose, a monitoring key 10 is actuated. Upon the actuation of this key contact 11 thereof is closed to cause the energization of relay 40, which thereupon causes the following operation to take place: (1) opens contact 42, thereby opening up the primary circuit including the induction coil primary 21 and the transmitter 25 to prevent outside noises from being induced into the secondary winding; (2) opens contact 43 thereby removing the ground from the middle point of the secondary winding and the junction point of the two resistances 35 and 36 to prevent the possibility of noises on the line due to such ground; (3) opens contact 44, thereby disconnecting the receiver 30 from bridged relation with sections 27 and 28; (4) closes contact 45, thereby connecting the receiver 30 in bridge of the low impedance section 26; and (5) closes contact 46, causing the operation of the slow-to-operate relay 41, which then cooperates with the monitoring key 10 to connect the tip and ring conductors 33 and 31 of the telephone set with the talking strands of the cord circuit. The secondary winding is now bridged across the talking strands of the cord circuit. As already explained the sections 27 and 28 of the secondary winding of the induction coil are of high resistance, so that when the receiver 30 is removed from bridged relation with these high resistance sections and connected in bridge of the low resistance section 26, the total impedance of the bridge across the talking strands of the cord circuit is very materially increased, thereby having less effect upon the transmission efficiency of the circuit between subscribers A and B.

It is to be observed that this invention provides an operator's telephone circuit in which a single induction coil may be employed for ordinary talking and receiving, and which may be then connected in bridge of a telephone line for monitoring purposes, and when so connected the effective imped-

ance of the bridge is materially increased to produce as little shunting effect for talking currents as possible.

What is claimed is:

1. In a telephone system, in combination, a telephone line, an induction coil having a primary and a secondary winding, a transmitter and a source of current in circuit with the primary winding, a receiver in operative relation to the secondary winding, a switch, a bridge including the secondary winding connected across the telephone line upon the actuation of the switch, a second switch controlling the connection of the bridge across the telephone line, and means effective upon the actuation of the second switch for altering the impedance of the bridge.

2. In a telephone system, in combination, a telephone line, an induction coil having a primary and secondary winding, a transmitter and a source of current in circuit with the primary winding, a receiver in operative relation to the secondary winding, a switch, a bridge including the secondary winding connected across the telephone line upon actuation of the switch, a second switch controlling the connection of the bridge across the telephone line, and means effective upon the actuation of the second switch for increasing the impedance of the bridge before the connection thereof to the telephone line.

3. In a telephone system, in combination, a telephone line, an induction coil having a primary and a secondary winding, a transmitter and a source of current in circuit with the primary winding, a receiver in operative relation to the secondary winding, a switch, a bridge including the secondary winding connected across the telephone line upon the actuation of the switch, a second switch controlling the connection of the bridge across the telephone line, and a relay responsive to the actuation of the second switch for increasing the impedance of the bridge before the connection thereof to the telephone line.

4. In a telephone system, in combination, a telephone line, an induction coil having a primary and a secondary winding, a transmitter and a source of current in circuit with the primary winding, a receiver in operative relation to the secondary winding, a switch, a bridge including the secondary winding connected across the telephone line upon the actuation of the switch, a second switch, a relay responsive to the actuation of the second switch for altering the impedance of the bridge, and a second relay controlled by the second switch for connecting the altered bridge to the telephone line.

5. In a telephone system, in combination, a telephone line, an induction coil having a primary and a secondary winding, a trans-

mitter and a source of current in circuit with the primary winding, a receiver in operative relation to the secondary winding, a switch, a bridge including the secondary winding connected across the telephone line upon the actuation of the switch, a second switch, a relay responsive to the actuation of the second switch for increasing the impedance of the bridge, and a slow-to-operate relay operating upon the response of the first relay for thereafter connecting the bridge to the telephone line.

6. In a telephone system, in combination, a telephone line, an induction coil having a primary and a secondary winding, a transmitter and a source of current in circuit with the primary winding, a receiver normally connected in bridge of a portion of the secondary winding, a switch when actuated causing the connection of the secondary winding to the telephone line, and means effective upon the actuation of the switch for connecting the receiver in bridge of another portion of the secondary winding.

25 7. In a telephone system, in combination, a telephone line, an induction coil having a primary and a secondary winding, a transmitter and a source of current in circuit with the primary winding, a receiver normally connected in bridge of a portion of the secondary winding, a switch when actuated causing the connection of the secondary winding to the telephone line, and a relay responsive to the actuation of the switch for connecting the receiver in bridge of another portion of the secondary winding.

8. In a telephone system, in combination, a telephone line, an induction coil having a primary and a secondary winding, a transmitter and a source of current in circuit with the primary winding, a receiver normally connected in bridge of a portion of the secondary winding, a switch, a relay responsive to the actuation of the switch for connecting the receiver in bridge of another portion of the secondary winding, and another relay controlled by the switch for thereafter connecting the secondary winding to the telephone line.

50 9. In a telephone system, in combination, a telephone line, an induction coil having a primary and a secondary winding, a transmitter and a source of current in circuit with the primary winding, a receiver normally connected in bridge of a portion of the secondary winding, a switch, a relay energized upon the actuation of the switch for connecting the receiver in bridge of another portion of the secondary winding, and a slow-to-operate relay operating upon the energization of the first relay for thereafter connecting the secondary winding to the telephone line.

10. In a telephone system, in combination, a telephone line, an induction coil having a

primary winding, a transmitter and a source of current in circuit with the primary winding, a secondary winding for the induction coil grounded at its middle point, a receiver normally connected in bridge of a portion of the secondary winding and in symmetrical relation to the ground thereof, a switch when actuated causing the connection of the secondary winding to the telephone line, and a relay responsive to the actuation of the switch for removing the ground from the secondary winding and connecting the receiver in bridge of another portion thereof.

11. In a telephone system, in combination, a telephone line, an induction coil having a primary winding, a transmitter and a source of current in circuit with the primary winding, a secondary winding for the induction coil grounded at its middle point, a receiver normally connected in bridge of a portion of the secondary winding and in symmetrical relation to the ground thereof, a switch, a relay responsive to the actuation of the switch for removing the ground from the secondary winding and connecting the receiver in bridge of another portion thereof, and another relay operating under control of the switch for thereafter connecting the secondary winding to the telephone line.

12. In a telephone system, in combination, a telephone line, an induction coil having a primary winding, a transmitter and a source of current in circuit with the primary winding, a secondary winding for the induction coil grounded at its middle point and comprising sections of high and low resistance, a receiver normally connected in bridge of a high resistance section of the secondary winding and in symmetrical relation to the ground thereof, a switch when actuated causing the connection of the secondary winding to the telephone line, and a relay responsive to the actuation of the switch for removing the ground from the secondary winding and connecting the receiver in bridge of a low resistance section thereof.

13. In a telephone system, in combination, a telephone line, an induction coil having a primary winding, a transmitter and a source of current in circuit with the primary winding, a secondary winding for the induction coil grounded at its middle point and comprising sections of high and low resistance, a receiver normally connected in bridge of a high resistance section of the secondary winding and in symmetrical relation to the ground thereof, a switch, a relay responsive to the actuation of the switch for removing the ground from the secondary winding and connecting the receiver in bridge of a low resistance section thereof, and a slow-to-operate relay operating under control of the switch and coöperating therewith for thereafter connecting the secondary winding to the telephone line.

14. In a telephone system, in combination, a telephone line, an induction coil having a primary winding, a transmitter and a source of current in circuit with the primary winding, a secondary winding for the induction coil comprising two sections of high and two of low resistance and having its middle point grounded, a receiver normally connected in bridge of the high resistance sections and 10 in symmetrical relation to the ground of the secondary winding, a switch, a relay energized upon the actuation of the switch for

opening the primary circuit, removing the ground from the secondary winding and connecting the receiver in bridge of one of 15 the low resistance sections, and a slow-to-operate relay operating upon the energization of the first relay and coöperating with the switch to thereafter connect the secondary winding to the telephone line. 20

In witness whereof I hereunto subscribe my name this 21st day of September, A. D. 1917.

KENNETH S. JOHNSON.
